U.S. Cl. D48—32

FIG. 1

FIG. 3

FIG. 4

FIG. 5

FIG. 6

FIG. 1 is a perspective view of a lens for boat anchor light showing my new design;

FIG. 2 is a second perspective view thereof;

FIG. 3 is a cross-sectional view taken on line 3-3 of FIG. 2;

FIG. 4 is a perspective view of a second embodiment of my design;

FIG. 5 is a second perspective view thereof;

FIG. 6 is a cross-sectional view taken on line 6-6 of FIG. 5.

The standard is shown in broken lines in FIGS. 1 and 4 for illustrative purposes only.

The characteristic features of my design reside in the combination of the specific exterior and interior configurations of the lens as best seen in FIGS. 3 and 6.

I claim:

The ornamental design for a lens for a boat anchor light, as shown and described.
